UNITED STATES PATENT OFFICE.

FRANK LUISA AND JAMES DI MATTEO, OF NEW YORK, N. Y.

TWIN LABEL CUTTER.

Application filed March 30, 1925. Serial No. 19,233.

To all whom it may concern:

Be it known that we, FRANK LUISA and JAMES DI MATTEO, citizens of the United States, residing at New York, in the county 5 of New York and State of New York, have invented certain new and useful Improvements in Twin Label Cutters, of which the following is a specification.

This invention relates to improvements in 10 label cutters, and it is the principal object of my invention to provide a label cutter or punching device for cutting a double stack of labels from sheets at one operation, and for simultaneously removing the waste 15 in order to prevent a clogging of the cutting machinery thereby.

Another object of the invention is the provision of a label cutter of this character including an adjustable blade, for removing 20 the waste.

A further object of the invention is the provision of a label cutting machine having a plurality of delivery chutes for the labels cut from the blank sheets by the machine.

A still further object of the invention is the provision of a plurality of adjustable hollow punching devices.

Other features and advantages of the invention will become more fully known as the 30 description thereof proceeds, and will then be specifically pointed out in the appended claims.

In the accompanying drawings forming a material part of this disclosure:

Fig. 1 is a front elevation of a label cutting machine embodying the novel and improved features according to the present invention.

Fig. 2 is a rear end view thereof.

Fig. 3 is a side elevation of the cutting end of the machine on an enlarged scale.

Fig. 4 is a cross-section on line 4—4 of Fig. 3.

Fig. 5 is a bottom plan view of the cutters 45 and co-operating parts.

Fig. 6 is a section on line 6—6 of Fig. 5.

Fig. 7 is a fragmentary sectional detail view of an adjustment device.

Fig. 8 is a section on line 8—8 of Fig. 3.

The machine equipped with the novel and improved label cutting mechanism can be of any suitable construction and including, for instance, the cross-head or plunger 10 to which the hollow dies or knives 11 and 12 are secured by means of the boss 13. A pitman 14 has secured thereto the plunger

10 and is operated from a crank shaft 15 journaled in bearings 16 and carrying at one end a fly-wheel 17 for regulating the movements of the crank-shaft. The entire 60 mechanism above described is carried by a support or body 18.

In the lower face of this body 18, two parallel grooves 19 and 20 are cut in which are displaceably arranged blocks 21 and 22 65 at the ends of adjusting screws 23 and 24, 25 and 26 extending out of the plane of body 18 and bearing there adjusting heads.

To the faces of blocks 21 and 22, the upper flanges 27 and 28 of the hollow cutter 70 dies, 11 and 12 are secured by means of bolts and nuts 29 which, in this manner, may be displaced across the body 18 by the proper manipulation of screws 23, 24, 25 and 26.

A pair of superposed delivery chutes 30 75 and 31 are secured to the body 18 at their angularly bent ends as at 32 and 33 and have their bent lower ends in communication with the dies 11 and 12.

The guides for the labels, during their 80 initial travel, in these delivery chutes are designated 34 and 35, and may be adjusted to conform to the size of the blades by adjusting screws 36 and 37 movable in slots 38 and 39 of plates 40 and 41, attached to guides 34 and 35. The chutes are made in two parts 85 overlapping at their ends and attached to each other by means of screws 42 and 43.

In order to prevent clogging by waste material, a waste cutting blade 44 is provided 90 having the appearance of a stretched U in side elevation, the upper ends of the shanks of which are attached to cylindrical blocks 45 and 46 working in casings 47 and 48 adjustably secured to the outer face of body 18. 95

The casings 47 and 48, have each lateral flanges 49 and 50 provided with slots 51 and 52 respectively in which adjusting screws 53 and 54 working, engaging with their lower ends in grooves 55 in the oppositely 100 disposed faces of the body 18. The reduced ends of blocks 45 and 46 extend out of casings 47 and 48 and carry locking nuts 56 and 57 on their upper screw-threaded ends 58.

Spring 59 are wound about the screw parts of 45 and 46 and engage with their upper ends the upper walls of casings 47 and 105 rest with their lower ends in the bottom thereof.

The operation of the device will be fully understood from the above descrip-

tion, the double dies and double delivery chutes will cut and deliver the double amount of labels as heretofore, and if an adjustment of these dies is desired this can 5 readily be made by means of the proper manipulation of screws 23, 24, 25 and 26.

The waste accumulating during the cutting operation will be cut and removed by means of the blade 44 which is adjustable 10 and cushioned.

It is to be understood that the device shown and described is an illustration of its preferred form only, and that it can be subjected to any changes such as fall within 15 the scope of the appended claims without departure from the spirit of the invention.

Having thus described our invention, what we claim as new, and desire to secure by Letters Patent, is:

20 1. Label cutting and punching machine, comprising a grooved body, a pair of hollow cutting dies, shoes for said dies adjustable in the grooves of said body, means for delivering the cut labels, and a means for 25 removing the waste paper after each operation of the cutting dies.

2. Label cutter, comprising a grooved body, two juxtaposed hollow cutting dies, shoes for said dies adapted to be displaced 30 within the grooves of said body, set screws for displacing said shoes for adjusting said dies in their relative positions to said body, a pair of adjustable delivery chutes for the 35 cut labels, and an adjustable waste remover and blade attached to said body between said dies.

3. In a label cutting and punching machine of the class described including a body and a pair of hollow, juxtaposed cutting dies adjustably held in said machine, a waste remover blade comprising a pair of 40 cushioned arms or shanks adjustably guided on said body and means for locking the parts in their relative adjusted positions.

4. In a label cutting and punching machine of the class described, including a grooved body and a pair of hollow juxtaposed cutting dies, adjustably held in said machine to said body, a waste paper removing blade of substantially stretched U-shape, 50 having upstanding cylindrical shank ends, a chamber receiving said ends, a stem formed with said ends extending through said chamber, locking nuts upon the upper threaded end of said stem and a spring wound about 55 said stem in said chamber, resting on said cylindrical shank ends and engaging the upper wall of said chamber, and means for displacing said chamber body within the grooves of said grooved body and for locking 60 the parts in their adjusted relative positions.

5. In a label cutting and punching machine of the class described, the combination of a grooved body adapted to be secured to a plunger of the machine, a pair of hollow, juxtaposed cutting dies, flanges on said dies, shoes to which said flanges are secured, adapted to slide within the grooves of said body, set screws for holding said 70 dies to said shoes, and set screws for displacing said shoes in said grooves and for holding the parts in their relative adjusted positions, a pair of superposed label delivery chutes, means for allowing an adjustment of 75 the height of said chutes, means for attaching said shoes to said body, a pair of chambered lugs, flanges on said lugs, means for displacing said lugs and for locking them in their adjusted positions in the grooves of 80 said body, a cushioned waste remover blade entering with its shanks, said chambered lugs and a means for adjustably securing said blade to said chambered lugs.

In testimony whereof we have affixed our 85 signatures.

FRANK LUISA.
JAMES DI MATTEO.
